CLAIM

The ornamental design for a bubbling bath mat, as shown.

DESCRIPTION

FIG. 1 is a top plan view of bubbling bath mat showing our new design;

FIG. 2 is a side elevational view thereof;

FIG. 3 is a side elevational view thereof, opposite that shown in FIG. 2;

FIG. 4 is an end elevational view thereof;

FIG. 5 is an end elevational view thereof, opposite that shown in FIG. 4; and

FIG. 6 is a bottom plan view thereof.
